AUTOMATIC FIDELITY CONTROL CIRCUITS

Rene A. Braden, Collingswood, N. J., assignor to
Radio Corporation of America, a corporation
of Delaware

Original application July 29, 1933, Serial No.
682,743. Divided and this application January
9, 1935, Serial No. 1,005

12 Claims. (Cl. 179—171)

My present invention relates to fidelity control arrangements for radio frequency signaling systems, and more particularly to automatic fidelity control circuits for radio receivers, and is a division of application Serial No. 682,743, filed July 29, 1933 now Patent No. 2,083,229.

It is one of the primary objects of my present invention to provide a method of automatically controlling the selectivity of a radio frequency signalling system whereby the system is more selective on weak signals than on strong ones.

Another important object of the present invention is to provide an automatic fidelity control for a radio receiver of the type wherein the resonance curve of a tunable network is automatically varied in response to the variation in amplitude of the received signal energy.

Another important object of the present invention is to provide an automatic selectivity control circuit for a radio receiver wherein the rectified signal energy of the receiver is utilized to vary the high frequency response characteristic of a resonant circuit preceding the receiver rectifier.

Still another object of the present invention is to provide a fidelity control arrangement for a radio receiver, the latter operating on a band pass network preceding a rectifier in such a manner that the resonance curve of the network is automatically varied to have a single resonance peak when weak, or distant, station signals are received, and a double peak when strong, or local, stations are received.

Another object of the present invention is to provide an automatic selectivity control circuit for a receiver wherein a rectifier automatically regulates the amount of damping introduced into a preceding tuned circuit, the damping being increased when receiving strong signals, and being decreased when receiving weak signals.

Still other objects of the present invention are to improve generally the efficiency of radio receiving systems, and particularly to provide automatic fidelity control circuits for radio receivers which are not only efficient and reliable in operation, but economically constructed and assembled in radio receivers.

The novel features which I believe to be characteristic of my invention are set forth in particularity in the appended claims, the invention itself, however, as to both its organization and method of operation will best be understood by reference to the following description taken in connection with the drawing in which I have

indicated diagrammatically several arrangements for carrying my invention into effect.

In the drawing,

Fig. 1 shows an embodiment of the invention as applied to a band pass network,

Fig. 2 shows a modification of the invention which is applied to the tuned input circuit of an amplifier.

Referring now to the accompanying drawing wherein like reference characters in the two figures designate similar circuit elements, there is shown in Fig. 1, in highly conventional form, a radio receiving system embodying one form of my invention. Broadly, it may be stated that the receiving circuit shown in Fig. 1 includes means for varying the selectivity of a receiving set, and which means comprises a signal actuated control tube.

In Fig. 1 there is shown an arrangement for securing automatic selectivity control wherein a damping action on one of the tuned circuits between amplifiers 6' and 7' is secured by the utilization of a feedback circuit. Between the screen grid amplifiers 6' and 7' there is connected a coupling network which comprises a pair of coupled tuned circuits 30 and 31. The tuned circuit 30 includes in a series arrangement a coil 32, the tuning condenser 33, and the coupling coil 34. The tuned circuit 31 includes in a similar series arrangement the coil 32', the tuning condenser 33', and the coupling coil 34'. The magnetic coupling M_1 between coils 34 and 34' is less than critical.

The rectifier 8, following amplifier 7', is shown as of the biased detector type. A resistor R is disposed in the grounded cathode lead of tube 8; the source B providing the positive potential for the plate of the detector tube. The audio component of detected signals is fed to any desired audio frequency utilization network. The selectivity control tube 35 is of the screen grid type, and has its plate circuit coupled to circuit 30 by the magnetic coupling M between coils 36 and 32. The operating direct current bias for the control tube 35 is dependent on the voltage of fixed bias source 38 and the variable potential drop across that portion of resistor R between ground and adjustable tap 50. The signal grid of tube 35 is connected to the negative terminal of bias source 38 through filter resistor R_1 ; the cathode of tube 35 being grounded. Signal voltage is impressed upon the signal grid of tube 35 through condenser 37. The coils 32 and 36 are so poled that the signal voltage, repeated through tube 35, is impressed on circuit 30 in 55

degenerative phase. That is to say, the effect of tube 35, as its gain increases, is to increase the damping of network 30-31. This results from the degenerative phase of the signal voltage fed back, through coil 36, to circuit 30.

The tube 35 feeds back signal voltage to the tuned circuit 30, and the feed-back polarity is opposite to that required for oscillation. Hence, there is a tendency to reduce the output of the receiving system as the received signal amplitude increases. The reduction of output is greatest at resonance, and therefore the over-all selectivity curve of the system is flattened into a band pass curve. By regulating the bias of tube 35 the sharpness of the selectivity curve can be altered. This is accomplished automatically by the signal so that the selectivity is inversely proportional to the signal strength. In other words, the auxiliary control tube 35 connected to the network between tubes 6' and 7', which network may be operating at intermediate frequency or at a much higher frequency, produces reversed feed-back, which in turn reduces the gain and pushes down the center of the resonance curve so as to make it broad and flat, or double-peaked. The bias on the control grid of tube 35 controls the reversed feed-back; accordingly, if the bias is high there is no feedback and the coupling network tunes sharply and has a normal gain.

In the absence of received signals the network 30-31 has a sharp single peaked resonance curve; the coupling M_1 being less than critical. Again, the gain of tube 35 will be a minimum, in this no-signal condition, due to the negative bias from source 38. Hence, the damping action on network 30-31, caused by the effect of the degenerative coupling M , will be a minimum, since substantially no feedback occurs through tube 35 when the negative bias is high.

When signals of weak amplitude, as from distant stations, are received, the bias on the grid of tube 35 will be high; this following from the fact that the negative bias source 38 overcomes the effect of the voltage developed in resistor R between ground and the grid tap 50. As the signal amplitude increases, this voltage across the portion of resistor R between ground and the grid tap from tube 35 increases; thus overcoming the effect of the negative bias from source 38 and increasing the gain of tube 35 as well as the reversed feedback effect.

A modification of the arrangement shown in Fig. 1 is represented in Fig. 2. The amplifier tube 7' is connected across the tuned circuit 40, the latter including the coil 41, the resistor R_2 and the tuning condenser 42. The function of the resistor R_2 is to broaden the tuning of the circuit 40. The control tube 35' provides regeneration which sharpens the resonance curve and increases the gain. The amount of regeneration is controlled by the control grid bias, or screen voltage if desired, of tube 35', the latter in turn depending on the signal strength.

In this form of the invention the resistor R' , which develops the signal-responsive bias for tube 35', is connected between ground and the negative terminal of detector plate voltage source B. The cathodes of tubes 35' and 8 are at ground potential, and tap 50' is connected from the signal grid of tube 35' to a desired point on resistor R' through filter resistor R_1 . The coil 36', in the plate circuit of tube 35', is magnetically coupled to coil 41, as at M_2 , in regenerative phase. Signal voltage is impressed on the signal grid, of tube 35' through condenser 37'. Normally, and

in the absence of signals, the gain of tube 35' is a maximum, since the voltage drop across resistor R' is then a minimum. Therefore, the regenerative feedback will be a maximum, and the effect of damping resistor R_2 will be compensated for to an extent sufficient to impart a sharp, single peak resonance curve characteristic to circuit 40.

With increasing signal strength the bias of tube 35' must be increased to reduce the regeneration. Several stages of this kind can be used in cascade. The function, then, of tube 35' of Fig. 2, is to regenerate in the tuned circuit 40, which may be a radio frequency or intermediate frequency stage which has high damping, so as to reduce the effective damping, and, thus sharpen tuning and increase gain when weak signals are being received. When strong signals are being received the regenerative feed-back to the circuit 40 is reduced, and hence the effective resonance curve of circuit 40 is flattened thereby increasing the fidelity of reception.

While I have indicated and described several systems for carrying my invention into effect, it will be apparent to one skilled in the art that my invention is by no means limited to the particular circuits shown and described, but that many modifications may be made without departing from the scope of my invention as set forth in the appended claims.

What I claim is:

1. In a receiving system, a pair of amplifier tubes, a tuned circuit coupling said tubes, said tuned circuit being resonant to a desired signal frequency, a rectifier, means for impressing signal frequency energy upon said rectifier, and means, responsive to variations in potential of the direct current component of the rectified output of said rectifier, for adjusting the response characteristic of said tuned circuit, said means including a device for regulating the damping of said tuned circuit, said damping regulating means consisting of a tube having its anode circuit reactively coupled to said tuned circuit to impress on the latter signal energy repeated through the said last tube, and its control grid connected to the output circuit of said rectifier, the constants of the last tube being such as to adapt it solely for non-rectifying signal repeater action, said coupling being such that the damping of said tuned circuit is regulated, and a signal frequency path connected between the control grid of said damping regulating tube and said tuned circuit for impressing signal energy upon said regulating tube.

2. A band pass network of the type comprising a pair of resonant circuits, each circuit being tuned to the operating carrier frequency, the circuits being coupled to provide a normally sharp, single peak resonance curve characteristic, reversed carrier energy feedback means connected in cyclic sequence with said circuits for damping the network sufficiently to impart to it a wide resonance curve characteristic, and means, responsive to signal amplitude variations, for automatically regulating the operation of said means.

3. A band pass network of the type comprising a pair of coupled resonant circuits having a normally sharp resonance curve characteristic, each circuit being tuned to the operating carrier frequency, reversed carrier energy feedback means connected in cyclic sequence with said circuits for damping the network sufficiently to impart to it a wide resonance curve characteristic, and a signal rectifier connected to said reversed

feedback means to render the latter inoperative when weak signals are transmitted through the network.

4. In a signal receiving system including a tube provided with an input circuit tuned to a desired signal frequency, damping signal feedback means operatively associated with the tuned circuit to impart a resonance curve characteristic to it which is relatively broad for strong signals, and 10 additional means responsive to a decrease in signal amplitude, directly controlling said feedback means in a sense substantially to minimize the feedback efficiency thereof whereby said characteristic is automatically made sharp for weak 15 signals.

5. In a signal receiving system including a tube provided with an input circuit tuned to a desired signal frequency, reversed signal feedback means operatively associated with the tuned circuit 20 to impart a resonance curve characteristic to it which is relatively broad for strong signals, and additional means, responsive to a decrease in signal amplitude, for substantially minimizing the effect of the first means whereby said characteristic is automatically made sharp for weak 25 signals.

6. In a signal receiving system including a tube provided with an input circuit tuned to a desired signal frequency, signal feedback means operatively associated with the tuned circuit to impart a resonance curve characteristic to it which is relatively broad for strong signals, and additional means including a signal rectifier tube connected to the feedback means, responsive to a decrease 35 in signal amplitude, for substantially minimizing the effect of the first means whereby said characteristic is automatically made sharp for weak signals.

7. A band pass network of the type comprising 40 a pair of coupled resonant circuits having a normally sharp resonance curve characteristic, each circuit being tuned to the operating carrier frequency, and reversed feedback means for damping the network sufficiently to impart to it a wide resonance curve characteristic, said means comprising a tube having its input and output circuits reactively coupled to said network, and

the output circuit being connected in the degenerative phase with said network.

8. A method of operating a signal transmission network of the type including at least two coupled circuits arranged in cascade and tuned to the same signal carrier frequency, which consists in impressing signals of a desired amplitude, and of said frequency, upon the network, and feeding back said signals from the output of the network to the input in degenerative phase to 10 maintain substantially uniform the amplification of the modulation frequencies of said carrier frequency energy transmitted through said network at said desired amplitude.

9. A method of operating an amplifier provided with a tuned input circuit having a normally sharp resonance curve characteristic, which consists in impressing signals upon the input circuit, feeding back signals without rectification for re-impression upon the input circuit substantially to widen said characteristic, and automatically controlling solely the feedback intensity in response to signal amplitude variations to regulate said characteristic.

10. A method of operating an amplifier having 25 a tuned input circuit provided with a predetermined resonance characteristic which consists in impressing signals upon the input circuit, feeding back signals in degenerative phase for re-impression upon the input circuit, and automatically controlling solely the feedback intensity in response to signal amplitude variations to regulate the shape of said characteristic.

11. In a radio receiver having an amplifier, a feedback circuit in said amplifier, a relay tube 35 connected to said circuit and controlling said feedback, and means responsive to the amplifier output energy for controlling said relay tube in accordance with signal strength, whereby the selectivity of said amplifier is altered.

12. In a radio receiver having an amplifier, a degenerative feedback circuit in said amplifier, a relay tube connected in said circuit and controlling said degenerative feedback, and means for controlling said relay tube in accordance 45 with signal strength, whereby the selectivity of said amplifier is altered.
